Primary Examiner — Kevin Rudzinski*Assistant Examiner* — Sean D Lough(74) *Attorney, Agent, or Firm* — Fish & Richardson P.C.(57) **CLAIM**

The ornamental design for the LED lamp, as shown and described.

DESCRIPTION

FIG. 1 is a perspective view of LED lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines (where present) in all Figs. illustrate portions of the LED lamp that form no part of the claimed design.

1 Claim, 7 Drawing Sheets(56)
